UNITED STATES PATENT OFFICE

JAMES B. WEIR, OF OAKWOOD HEIGHTS, AND PAUL BERTELL, OF BUFFALO, NEW YORK;
SAID WEIR ASSIGNOR TO STANDARD MIRROR COMPANY, INC., OF BUFFALO, NEW
YORK, A CORPORATION OF NEW YORK

DESIGN FOR A COMBINED REAR-VISION MIRROR AND INSTRUMENT CASING

Application filed October 23, 1929. Serial No. 33,148. Term of patent 14 years.

To all whom it may concern:

Be it known that we, JAMES B. WEIR and PAUL BERTELL, a subject of the King of Great Britain, and a citizen of the United States, respectively, residing at Oakwood Heights, Staten Island, in the county of Richmond and State of New York, and at Buffalo, in the county of Erie and State of New York, respectively, have invented a new, original, and ornamental Design for Combined Rear-Vision Mirror and Instrument Casing, of which the following is a specification, refer-

ence being had to the accompanying drawing, forming part thereof.

The accompanying drawing is a perspective view of a combined rear vision mirror and instrument showing our new design.

We claim:

The ornamental design for a combined rear vision mirror and instrument casing, as shown.

JAMES B. WEIR.
PAUL BERTELL.
